UNITED STATES PATENT OFFICE.

OTTO M. DU BRAU, OF BALTIMORE, MARYLAND.

DUST-COLLECTING ATTACHMENT FOR RADIATORS.

1,279,300.

Specification of Letters Patent. Patented Sept. 17, 1918.

Application filed January 17, 1916. Serial No. 72,540.

To all whom it may concern:

Be it known that I, OTTO M. DU BRAU, a citizen of the United States, residing at Baltimore, State of Maryland, have invented certain new and useful Improvements in Dust-Collecting Attachments for Radiators, of which the following is a specification, reference being had therein to the accompanying drawing.

10 This invention relates to improvements in the art of radiators and has for its object the provision of an attachment capable of collecting the dust carried by the air and circulating around and through the radiator under normal working conditions. Experience has shown that as an incident to the circulation of air throughout a room heated by a system involving the use of radiators, the dirt and dust accumulations on the radiator are picked up by the air and deposited on the ceiling or in the corners adjacent to the ceiling of the room. This is objectionable in any case but far more so, where the walls are of a relatively expensive decorated type.

My improvements overcome the objections hereinabove noted in that the attachment will permit the cold air to pass to the radiator from a relatively low point and upwardly therefrom as heated through a dust collecting medium to purify the air as it rises in heated condition and spreads throughout the room.

35 The invention comprehends an attachment conveniently of a knock-down nature, though not essentially so, comprising side and front and rear panels and a top section, adapted when assembled in operative position to leave a lower portion of the front of the radiator exposed for direct admission of the air, but enveloping the ends, upper portion of the front, rear and top of the radiator to compel the heated and dust or dirt-laden air to pass through a filtering or screening means capable of relieving the air of the objectionable particles borne thereby, prior to the liberation of the air thus purified into the room, the result being the elimination of unsightly or soiling accumulations 50 on the walls or ceiling of the room as well as purifying the air for the consumption of the room occupants.

In the accompanying drawings forming part hereof, I have illustrated the preferred embodiment of my invention and the details

in construction and arrangement of parts will be apparent to persons skilled in the art from an inspection of such drawings when read in connection with the specific description hereinafter contained.

60 In the drawings:—

Figure 1 is a perspective view of a radiator having the attachment in place therearound.

Fig. 2 is a vertical sectional view through the attachment, taken lengthwise thereof.

Fig. 3 is a horizontal section on a line through the flanges of the top panel, looking in a downward direction, and,

Fig. 4 is a perspective view of a pair of 70 the sections of the attachment separated to show the manner of detachably connecting the same together and the filtering devices on the inside of the attachment.

Referring more specifically to the drawings wherein like reference letters designate corresponding parts in the several views, A represents a radiator of any type, that shown being the conventional hot water or steam radiator.

B represents end panels of my improved radiator attachment extending substantially the full depth and height of the radiator; C are the front and rear panels thereof, the former covering the front upper portion of the radiator to leave the lower portion of the latter open or exposed, as indicated at D, and E is the top panel, these panels, when assembled, effectually housing the radiator, save at the lower front portion thereof, as 85 mentioned, for the purpose as will presently appear.

The panels B, C and E, may be made of any suitable material, preferably metal, contoured and decorated to present a pleasing 90 appearance or ornamentation in keeping with other surroundings.

Each panel comprises an open frame F having the open interior thereof bridged or faced by open work metal ornamentation as 100 fragmentarily illustrated at G and on the rear of each panel the desired filtering devices are mounted. These filtering devices comprise what may be termed a primary filter H and an auxiliary filter J, the former being composed of a relatively closely woven cotton or similar cloth capable of catching the larger particles of dirt carried by the air passing therethrough, and the latter being composed of a highly fibrous substance such 105 110

2
as a woolen or similar cloth or sheet capable of collecting the finer dust carried by the air. The edges of the primary filter H hang loose so as to overlap the auxiliary filter J, and in 5 operation close the marginal spaces there-between.

Each filtering sheet carries at its upper and lower edges a rod K, projecting at its opposite ends beyond the side edges of the 10 sheet so as to engage over brackets L provided for the reception of said ends. Four pairs of these hooks are provided on the rear face of each panel, the upper pairs opening upwardly and the lower pairs opening 15 downwardly so that all that is necessary to assemble the sheets on the panels is to slip one rod of the sheet into one pair of the brackets and draw the sheet relatively taut to enable the rod at the opposite 20 end of the sheet to engage the complementary pair of brackets when by the tension of the sheet, the rods will be firmly held in seated relation with respect to the brackets and preserved in working condition 25 until intentionally and forcibly removed. The two pairs of brackets for the outermost filter sheet or strip are arranged at a slightly less distance apart than the corresponding pairs of brackets adapted to 30 receive the innermost filter sheet so that the two sheets and their respective fastening devices are positioned to constitute no obstruction or interference with each other.

In assembling the device, I utilize inter- 35 fitting socket and hook devices enabling easy and expeditious coupling of the members together as well as separation thereof for the purpose of storing or shipping, the sockets being indicated at M and the hooks 40 at N, the sockets being open at the upper portion thereof so that hooks to engage therewith may be introduced into the sockets by slightly raising the panel bearing the hooks, then dropping the same after the 45 admission of the hooks into the open portions of the sockets, thus accomplishing an interlocking relation as will be recognized. The top panel E has a depending marginal flange O adapted to encompass the upper 50 edges of the front, end and rear panels, to retain the top in place, while at the same time effectually holding the front and end panels in operative association when inter-fitted with each other.

55 The panels, as hereinabove stated, are preferably formed of metal, the end panels B having inwardly turned flanges at their front and rear vertical edges adapted to overlie the front and rear faces respectively 60 of the front and rear panels, so that as the hook members N engage the downwardly tapering socket portions M, the tendency is to wedge the flanges of the end panels and the front and rear panels together to form 65 vertical closed joints, and the wedge shape

of the hooks causes the end panels to be drawn inwardly to abut the heads of the hooks.

Although standard radiators are supposed to be of an approximate size, the maximum 70 length of the same varies within slight limits, and to allow for this the hook members N are provided with adjustable shanks n, fitting sleeves n' rigidly secured to the front and rear panels and the shanks being 75 held in adjustable relation to the sleeves by screws n". I have found that cheese cloth is a good material to employ for my primary filter and that any closely woven material, preferably wool or silk will 80 constitute an effective auxiliary filter for catching the finer particles carried by the air, the air of course being relatively free to pass through the primary filter but considerably retarded in its passage through 85 the auxiliary filter to enable the collection of the finer particles referred to and preventing their escape to the atmosphere.

Of course it will be understood that 90 where I have herein referred to the front panel as being of less depth than the rear and end panels, so as to leave an unobstructed lower front portion, it is not with the idea that the invention is restricted to such a special formation nor to any idea 95 of mere ornamentation, because the front panel may well extend the full depth of the radiator, as in the case of the other panels and may be provided with the filter material throughout if desired, and as previously noted the entire attachment may be formed with or without ornamentation, as occasion may suggest or require. In this connection it will be noted that in the drawings the panels may be provided with feet 100 at their lower ends or cut out to provide open spaces of several inches between the same and the floor to permit air to pass freely therebeneath, especially in instances where one or more of the end panels are 110 formed to fit over the usual supply or discharge pipe.

While I have herein disclosed a particular embodiment of my invention, it will be clear that the invention may be embodied in other 11 forms and devices as may be in keeping with the scope of the hereto appended claims.

What is claimed is:

1. A dust collector attachment for radiators formed of relatively rigid open-work 12 material affording passage of air therethrough, and dust collecting means behind the said open work comprising a sheet of filtering material, and means at the opposite ends thereof for detachably securing the 13 same in place upon the frame work.

2. A dust collector attachment for radiators formed of relatively rigid open-work 14 material affording passage of air therethrough, dust collecting means behind said 15

open work comprising a sheet of filtering material, and means at the opposite ends thereof for detachably securing the same in place, said means comprising a pair of supporting rods, and brackets over which the rods may be engaged.

3. A dust collector attachment for radiators formed of relatively rigid open-work material affording passage of air there-
10 through, dust collecting means behind said open-work comprising a sheet of filtering material, and means at the opposite ends thereof for detachably securing the same in place, said means comprising a pair of sup-
15 porting rods, brackets over which the rods may be engaged, the brackets at the oppo- site ends of the sheet facing in opposite di- rections, and the rods being held therein by rendering the filtering sheet taut.

20 4. A dust collecting attachment for radiators formed of relatively rigid open-work material and filtering means behind said open-work material comprising a primary filter for relatively large particles, and an
25 auxiliary filter for relatively finer particles, the said filters being of a different mesh, and means for securing the filters in place.

5. A dust collecting attachment for radiators formed of relatively rigid open-work
30 material and filtering means behind said open-work material comprising a primary filter for relatively large particles, an aux- illiary filter for relatively finer particles, and means for securing the filters in place, the
35 filters being in sheet formation and the se- curing means being located at the opposite ends of the sheets for detachably holding them in place.

6. A dust collecting attachment for radi-
40 ators formed of relatively rigid open-work material and filtering means behind said open-work material comprising a primary filter for relatively large particles, an aux- illiary filter for relatively finer particles,
45 and means for securing the filters in place, the filters being in sheet formation and the se- curing means being located at the opposite ends of the sheets for detachably holding

them in place and consisting of rods adapted to engage oppositely facing brackets.

7. A dust collecting attachment for radiators formed of relatively rigid open-work material and filtering means behind said open-work material comprising a primary filter for relatively large particles, an aux- illiary filter for relatively finer particles, and means for securing the filters in place, the filters being in sheet formation and the se-
50 curing means being located at the opposite ends of the sheets for detachably holding them in place and consisting of rods adapted to engage oppositely facing brackets, the
55 brackets for one sheet being disposed at a less distance apart than the brackets for the other sheet to prevent interference one with the other.

8. A dust collecting attachment for radiators formed of relatively rigid open-work material and filtering means behind said open-work material comprising a primary filter permitting the dust laden air to pass therethrough while collecting the coarser particles from the air, and an auxiliary finer filter substantially retarding the passage of air so as to collect the finer particles of dust
70 or the like therefrom, said primary and auxiliary filters being separated to provide a substantial space therebetween.

9. In a dust collecting attachment for radiators, the combination with an inclosing
80 member adapted to surround a radiator, said member carrying dust collecting means, and being formed of panels some of which are flanged to receive over their flanges the ad- jacent edge portions of other panels and al- low a substantial adjustment of said edge portions with respect to said flanges with-
85 out separation to break the joint therebe- tween, and interfitting separable adjustable attaching devices for securing the panels to-
90 gether in the various positions of adjust- ment of the panel edge portions over the panel flange portions.

In testimony whereof I hereunto affix my signature.

OTTO M. DU BRAU.
